UNITED STATES PATENT OFFICE.

CARL A. JACOBY, OF WARREN, OHIO, ASSIGNOR TO THE AMERICAN FOLDING MACHINE COMPANY, OF WARREN, OHIO, A CORPORATION OF OHIO.

PAPER-FEEDING DEVICE.

1,115,675.

Specification of Letters Patent.

Patented Nov. 3, 1914.

Application filed January 29, 1914. Serial No. 815,274.

To all whom it may concern:

Be it known that I, CARL A. JACOBY, of Warren, in the county of Trumbull and State of Ohio, have invented certain new and useful Improvements in Paper-Feeding Devices; and I do hereby declare the following to be a full, clear, and exact description of the invention, such as will enable others skilled in the art to which it appertains to make and use the same.

The primary object of this invention is to provide in a timed paper handling device, means for preventing stock being improperly fed, that is to say, at the wrong time, thereby avoiding the waste which occurs from uneven folding and printing out of register. It is well-known that if stock is fed at the wrong time it will be out of register either for printing or folding.

In the accompanying drawing, Figure 1 is a side elevation, with parts omitted showing, the feed stops and drop-roll raised. Fig. 2 is a similar view showing the parts in the position they occupy when feeding, that is to say, with the drop-roll and stops lowered and the guards raised. Fig. 3 is a plan view with the drop-roll omitted.

Referring to the drawing, 1 designates a feed-roll which is located in the feed path at the end of feed table 2 onto which the stock may be fed by any suitable means, the periphery of such feed-roll intersecting the plane of the feed table.

3 designates a series of stops in rear of the feed-roll and designed, when raised, to project above or through the feed path and likewise above the periphery of the feed roll. By the term "rear" reference is meant to the delivery side of the feed-roll as distinguished from the receiving side thereof.

These stops are raised when a drop-roll 4 is elevated out of working engagement with the feed-roll, as shown in Fig. 1, and likewise when such drop-roll is lowered stops 3 are moved out of the feed path to allow the stock to be fed by the conjoint action of the two rolls. I have shown the stops 3 when raised, as in Fig. 1, as being in close relation to the opposed portions of the rolls 1 and 4 by which the stock is engaged.

Simultaneous with the lowering of the drop-roll and the withdrawal of the stops a series of guards 5 is caused to intersect the plane of the feed path in front of the feed-roll so that if stock should be fed while the

co-acting rolls are in operation it will be arrested by the guards and prevented from being taken up by the feed-roll. By the term "in front" reference is meant to the receiving side of the feed-roll as distinguished from the delivery side thereof. As soon as the drop-roll is raised and the stops are brought into their effective positions the guards will be lowered out of the way and allow the stock arrested thereby to pass to the stops in position to be taken up by the feed roll. The stops are sufficiently beyond the center of the feed-roll to allow the stock to be gripped between the two rolls. Likewise the guards are sufficiently in front of the rolls to prevent the latter from taking hold of the stock while arrested by such guards.

I do not restrict myself to any particular means of construction or arrangement for bringing about the necessary movements of the stops, the drop-roll and the guards. According to the means shown the stops are formed on the free ends of arms 6 which are fast on a shaft 7 which may be partly reciprocated by any suitable means, such arms being bent or curved to partly encircle the feed-roll shaft so that they may be positioned between peripheral enlargements of the feed-roll. This shaft may also cause the raising and lowering of the drop-roll, the supporting frame of the latter being connected by a link 8 to an arm 9 of said shaft. The guards 5 are shown as consisting of fingers carried by a spring-held shaft 10 which is partly rotated, as against the tension of its spring, by a tappet 12 of shaft 7 engaging a tappet 13 of shaft 10. When the former shaft is turned to raise the stops and the drop-roll, shaft 10 is turned by its spring to withdraw the guards.

The advantages of my invention will be readily appreciated by those skilled in the art. By means thereof waste of paper, resulting from irregular feeding, is avoided.

I claim as my invention:

1. A feeding device comprising intermittently co-operating feed-rolls, movable stops for arresting stock between opposite portions of said feed-rolls when the latter are inactive, and guards for arresting stock in front of said feed-rolls when the latter are in operation and said stops are withdrawn.

2. A feeding device comprising a feed-roll, a drop-roll for co-operating therewith,

stops designed to be moved into the feed path of stock when said drop-roll is raised to arrest stock between opposite portions of said feed-rolls, and guards designed to be moved into such feed path in front of the feed-roll when said stops are withdrawn and said drop-roll is in working relation to said feed-roll.

3. A feeding device comprising a feed path, a feed-roll intersecting such path, a second roll designed to be moved into and out of working engagement with said feed-roll, stops capable of being moved into said path in rear of said feed-roll when said second roll is out of engagement and to be withdrawn when such roll is in engagement, and guards capable of being moved into said path in front of said feed roll when said rolls are in working engagement.
4. A feeding device comprising a table, a feed-roll having its periphery intersecting

the feed path, a reciprocating shaft, stops carried by said shaft and capable of being moved into and out of said feed path, a drop-roll for coöperating with said feed-roll, means connecting said drop-roll to said shaft, a spring-held shaft, guard fingers carried by said shaft and designed to project into the feed path when said stops are withdrawn therefrom and said drop-roll is in working engagement with said feed-roll, and means carried by the first mentioned shaft for actuating said spring-held shaft in one direction.

In testimony whereof, I have signed this 35 specification in the presence of two subscribing witnesses.

CARL A. JACOBY.
